KNITTING MACHINE

Albert X. Desmonds, Indianapolis, Ind., assignor
to Real Silk Hosiery Mills, Inc., Indianapolis,
Ind., a corporation of Illinois

Application October 20, 1938, Serial No. 235,933

3 Claims. (Cl. 66—129)

My invention relates to full-fashioned hosiery knitting machines of the Wildman single-unit type, and more particularly to stop mechanisms for yarn carriers of such machines.

Such full-fashioned hosiery knitting machines of the single-unit type are illustrated in a number of patents, among which are the Howie and Krieble Patent No. 1,982,991 and the Howie Patent No. 1,989,232, granted respectively on December 4, 1934, and January 29, 1935.

It is an object of my invention to provide for a yarn-carrier of such a machine a central-group stop which both may be set in stop and non-stop positions and may be moved by suitable operating mechanism toward or away from the central line of the machine; so that when in stop position it may stop the inward movement of the yarn-carrier at different distances from the center line, as to provide a tapering reinforcement, but may be moved to non-stop position to permit the yarn-carrier to travel the full width of the stocking as controlled by end stops, as to permit the reinforcement to be continued for that full width.

In carrying out my invention, I provide a special central-stop mechanism for at least one, or more if desired, of the endless bands on which the several yarn-carriers are mounted—as for the #3 and/or #4 carrier-bands in the seven-yarn machine illustrated. This special central-stop mechanism, for each carrier band for which it is provided, includes a horizontally slidable member which may be moved lengthwise of the back stretch of that carrier band; that horizontally slidable member carries a stop which is movable into "stop" position in which it is in the path of a dog on that carrier band, to stop that carrier-band when the dog strikes the stop, and which is movable also into "non-stop" position in which it is out of that path and so permits the dog to pass it without being stopped; and that stop has an operating mechanism to move it either to stop position or to non-stop position, which operating mechanism conveniently is one which requires the horizontally slidable member carrying the stop to be in definite longitudinal positions in order for the operating mechanism to move the stop to stop and non-stop positions respectively.

The accompanying drawings illustrate my invention: Fig. 1 is a plan of a single-unit full-fashioned-hosiery-knitting machine equipped with my invention, with all of the mechanism above the carrier bands and the rotary reciprocatory operating-screw or draw-bar omitted

except the stop mechanisms and their operating means, and with the observer standing at the front of the machine; Fig. 2 is a fragmental plan, on a somewhat larger scale, of the stop mechanism embodying my invention, together with fragments of the several carrier bands, here shown as seven in number, with the observer standing at the rear of the machine; Fig. 3 is a fragmental vertical section on the line 5—5 of Fig. 2; Fig. 4 is a fragmental vertical section on the line 4—4 of Fig. 2; Fig. 5 is a fragmental vertical section on the line 5—5 of Fig. 3; Fig. 6 is a rear elevation of the upper part of the operating mechanism for the central stops; Fig. 7 is a fragmental vertical section on the line 7—7 of Fig. 6, with the addition that some of the lower parts of the operating mechanism are also shown; Fig. 8 is a fragmental elevation of the vertically movable double rack and its two associated pinions that operate the horizontally movable racks of the stop-carriers; Figs. 9, 10, 11, 12, and 13 are a series of fragmental views showing the different positions of a stop embodying my invention, and its carrying and operating mechanism, with Fig. 11 showing some additional associated mechanism including an associated pair of central-group stops that may be moved to stop and non-stop positions but are at fixed distances from the center of the knitting machine; Fig. 14 is a diagrammatic view of the leg-section of a stocking blank, an illustrative product of a machine embodying my invention, to show the movements of the different yarn-carriers in knitting it; and Fig. 15 is a similar diagrammatic view of the foot-section of that stocking blank, together with the lower part of the leg-section after the heel tabs have been turned.

In the seven-yarn machine shown, there are seven yarn-carriers or thread-guides 20, fed from the usual yarn spindles (not shown), and each of them is mounted on an endless thin-sheet-steel flexible band 21 set on edge. These endless flexible bands 21 have parallel straight front stretches which are very close together and which carry the thread-guides 20, and parallel straight rear stretches which are spaced farther apart and through which the operating mechanism works to move the endless flexible bands and their associated thread-guides, as is clear from Fig. 1; and they are mounted on edge on stationary end-plates 22, and suitably guided while kept taut, in the general manner shown in the aforesaid Howie and Krieble Patent No. 1,982,991. The individual endless flexible bands

21 shown are numbered as #1 to #7 inclusive, the outermost band (the front-most band on the front stretch and the rearmost band on the rear stretch) being #1, and the innermost band (the rearmost band on the front stretch and the 5 frontmost band on the rear stretch) being #7. The number of bands may of course vary as desired.

Each of the endless yarn-carrier bands 21 is provided with a dog 25, by which that endless band may be reciprocated along its own endless length by a rotary reciprocating operating-screw or draw-bar 26 through mechanism of the general character set forth in the aforesaid Howie and Krieble Patent No. 1,982,991. In that reciprocation, the thread-guides 20 are moved with their respective endless bands 21, to lay the desired thread or yarn in proper association with the usual needles and sinkers (not shown) of the knitting machine. The particular endless band or bands 21 which are operated on any stroke are selected by the usual selector mechanism, known in connection with the Wildman machine and shown in the said Howie and Krieble patent; and the length of each stroke of an endless band and its associated thread-guide 20 is controlled by stops which stop the movement of the proper dog 25 and so stop the movement of the endless band 21 and thread-guide 20 associated with that particular dog 25, by releasing such dog from its operating mechanism in known manner when the dog strikes a stop.

The stops consist of three general groups. Two end groups 31 and 32 are selvage stops, located near the left-hand and right-hand ends respectively of the rear stretches of the endless bands 21, to stop the yarn-carriers or thread-guides 20 at the right-hand and left-hand ends respectively of their movements (Fig. 1) at the locations where the selvages are to be formed. A central group of stops 33 is located between the end groups or selvage stops 31 and 32, to stop the yarn-carriers and their thread-guides 20 at intermediate points between the selvages, and so to locate the inner edges of the heel-tabs and of the reinforcements.

The two end groups 31 and 32, of selvage stops, are simultaneously movable toward or away from the center of the machine by an operating screw 34, which has a right-hand thread co-operating with one end group of stops and a left-hand thread co-operating with the other end group of stops; so that when the screw 34 is turned in one direction it causes both end groups of stops to move toward the center of the machine, and when it is turned in the other direction it causes both end groups of stops to move away from the center of the machine. The screw 34 is operated under the control of suitable pattern mechanism, already known, to obtain the desired narrowing of the stocking blank at the proper points in its length. The stops of the end groups of stops 31 and 32, or at least some of them, may be suitably raised out of the paths of the associated dogs 25 by releasing levers 36, to permit the associated dogs to pass the end stops to their various home positions at the left-hand and right-hand ends (Fig. 1) of the machine, to wait in those home positions until the pattern mechanism again puts them and their associated endless bands and yarn-carriers into operation.

In general, the mechanism so far described is known.

My invention is mainly concerned with certain individual stop mechanisms of the central group

5 of stops 33, which is not movable as a group and is not actuated by the operating screw 34; and with the new operations consequentially obtainable. I have illustrated that invention in connection with the central-group stops for both the #3 and #4 endless bands 21; but my invention may be and commonly is used with only one of those endless bands, such as #4, and may be used with any of the endless bands and with any desired number of them.

The reason those endless bands #3 and #4 were chosen to illustrate my invention is because of a common arrangement of yarns in the various yarn-carriers or thread-guides in the seven-yarn machine. That arrangement, with the yarns numbered as are their respective thread-guides and endless bands, is as follows:

#1 forms the welt 37, and is usually of silk or cotton.

#2 forms the toe 38, and is usually of silk or cotton.

#3 helps to form the heel-tab 39 and the reinforcement or splice 40 just above it, and the cradle portion 41, at the right of the stocking blank, and is commonly of heavier silk or cotton.

#4 helps to form the heel-tab 42 and the reinforcement or splice 43 just above it, and the cradle portion 44, at the left of the stocking blank, and is commonly of silk or cotton of the same weight as #3.

#5, #6, #7 form the main body 45 of the stocking, and are commonly of silk, and for the most part each of those three yarns is used every third course. In addition, these three yarns help form 35 the reinforcements 40 and 43 and the cradle portions 41 and 44; and the #6 and #7 yarns help form the heel-tabs 42 and 39 respectively.

The #5, #6, and #7 main yarns or threads, of 40 silk, are usually present not only in the body 45 of the stocking, where they are used alone, but also in those parts 39 to 44 where the #3 and #4 yarns or threads are present; so that the #3 and #4 45 yarns or threads are thus truly reinforcements.

The arrangement just described will be clear 45 from Figs. 14 and 15, which show a stocking blank, made however in accordance with my present invention, as it comes welt-first from the machine.

By my invention I may follow the general arrangement of threads above noted; but in addition I can provide not only non-center-passing reinforcements of varying width but also additional and full-width reinforcements—such as a reinforcement 47 (Fig. 15) which extends for the full 55 widths of the stocking blank, as for any desired number of courses immediately back of the toe 38. That additional reinforcement 47 is shown as provided with the #4 yarn or thread, the yarn-carrier or thread-guide for which in that portion of the operation travels the full length of the stroke as determined by the proper end or selvage stops 31 and 32; and during that full travel of the #4 60 thread-guide, the #3 thread-guide may if desired remain at rest in its home position.

65 My new mechanism permits this and various other new operations to be obtained.

The central group of stops 33 as a whole is carried by a stationary frame-portion 50, which midway of the machine extends over the rear 70 stretches of the endless bands 21. A plate 51 hung from that frame-portion 50 furnishes a support on which rests two slides 53 and 54, which lie over and extend along the rear stretches of the #3 and #4 endless bands 21. The two slides 53 and 54 are provided respectively with racks 55

and 56, which have their rack teeth upward to mesh with pinions 57 and 58 respectively mounted on shafts 59 and 60 suitably mounted in the stationary frame-portion 50. The shafts 59 and 60 are provided at the rear (in the machine and as seen in Fig. 1, although at the front in Fig. 2,) with pinions 61 and 62, which lie in the same plane transverse to the shafts 59 and 60 and mesh with opposite sides of a vertically movable double-rack bar 63 that lies between them. This construction of racks and slides, as so far described, may be substantially that of the Howie Patent No. 1,989,232 already mentioned.

The vertically movable double-rack bar 63 is provided at its lower end with a roller 64, by which it co-operates with a cam 65 on a selector shaft 66, which makes one complete rotation for each stocking-knitting cycle; so that by that rotation of such shaft 66 and cam 65 the double-rack bar 63 may be raised and lowered in conformity with the contour of the cam 65, which is shown in the position at the end of the knitting of the heel-splices. Raising the double-rack bar 63 acts through the pinions and racks referred to to move both slides outward, the slide 53 to the right and the slide 54 to the left as seen in Figs. 2, 3, and 9 to 13; and lowering the double-rack bar 63 acts through those pinions and racks to move both slides inward, the slide 53 to the left and the slide 54 to the right as seen in those figures. (It is exactly the reverse of that as to right and left as seen in Fig. 1.) The cam 65 may vary in contour in accordance with the shape of the reinforcements desired.

The two slides 53 and 54 carry vertically movable stops 71 and 72. Each stop is mounted in one end of its carrying slide, and is movable to an upper or non-stop position and to a lower or stop position; in either of which positions it is held against accidental displacement by a spring-pressed ball 73 operating in suitable positioning notches on its edge. As seen in Figs. 2, 3, and 4, and in Figs. 9-13, (for it is exactly the reverse in Fig. 1), the stop 71 is mounted in the slide 53 near the right-hand end of that slide, and the stop 72 is mounted in the slide 54 near the left-hand end of that slide. When the stop 71 or 72 is down, or in stop position, it is in the path of the dog 25 on the endless band which lies directly beneath it; and so is in position to be engaged by the projection on the top of that dog 25, (see Fig. 3), to stop the dog in its movement toward the middle of the machine and thus to stop the endless band 21 and the yarn-carrier or thread-guide 20 associated with that particular dog 25. But when the stop 71 or 72 is up, or in non-stop position, it is out of the path of the associated dog 25, so that that dog and its associated endless band 21 and yarn-carrier or thread-guide 20 may travel for the full stroke as determined by the proper end stops (selvage stops) 31 and 32.

The stops 71 and 72 are provided with laterally projecting operating pins 75 and 76 respectively, which project outward through slots in the side walls of the slides 53 and 54 respectively. The pin 75 projects toward the rear of the machine and of Fig. 1, and so toward the front of Figs. 2, 3, and 4; and the pin 76 projects toward the front of the machine and of Fig. 1, and so toward the rear of Figs. 2, 3, and 4. (In viewing these figures, it is to be remembered that for Fig. 1 the observer is standing at the front of the machine, and that for Fig. 2 the observer is standing at the rear of the

machine.) It is by these operating pins 75 and 76 that the stops are moved upward or downward.

But for such upward or downward movement, with the mechanism shown, the associated slides 53 and 54 must be in their proper longitudinal positions. The stops must be rather close to the center of the machine in order to obtain an upward movement of the stop, and farther but not too far from such center in order to obtain a downward movement.

The upward movement of the stops is obtained by lifting levers 77 and 78. When the stops 71 and 72 are in their innermost positions, nearest the center of the machine, their respectively associated pins 75 and 76 overlie the inwardly projecting ends of those lifting levers 77 and 78 respectively. (See Figs. 11 and 12.) If those inwardly projecting ends of the lifting levers are then raised (see Fig. 13), they engage the pins 75 and 76 respectively to lift the associated stops 71 and 72 from their lowermost or stop positions to their uppermost or non-stop positions.

The lifting levers 77 and 78 are mounted on carrying bars 79 and 80 respectively; and they are provided with springs 81 which tend to hold their inwardly projecting ends in their lowermost positions, determined by pins 82 mounted on said carrying bars and located in movement-limiting notches provided in the outer ends of those lifting levers. The two carrying bars 79 and 80 are suitably mounted on and beneath the stationary frame-portion 50, as by being set in transverse slots thereof and held in place by attaching screws 83.

The lifting levers 77 and 78 have their inwardly projecting ends offset from the planes of the levers proper; so that those offset ends will underlie the pins 75 and 76 in position to engage them when the stops 71 and 72 are close to the center of the machine, but so that the pins 75 and 76 may clear the bodies of the lifting levers 77 and 78 as the stops 71 and 72 are moved outward away from the center of the machine, as to the outer dotted-line positions of Figs. 2 and 3 and the positions of Figs. 9, 10, and 11.

When the stops 71 and 72 are moved outward from their innermost positions (of Figs. 12 and 13) to the intermediate position shown in Figs. 9 and 10 (although that intermediacy is not essential), the operating pins 75 and 76 come into position under depressing fingers 85 and 86 respectively. These depressing fingers also have portions 87 and 88 which respectively overlie the outer ends of the lifting levers 77 and 78 at all times. Thus whenever the depressing fingers 85 and 86 are moved downward (Figs. 10 and 13) they engage and move downward the outer ends of those lifting levers, to raise the inner ends of the latter. This will cause a lifting of the stops 71 and 72 if at that time the pins 75 and 76 are over those inner ends (as in Figs. 12 and 13); but if at that time those pins are under the ends of the depressing fingers 85 and 86 (as in Figs. 9 and 10), those depressing fingers will act directly on the pins 75 and 76 to push them and their associated stops 71 and 72 downward.

The depressing fingers 85 and 86 are mounted on the forwardly projecting ends of the two outermost stop-operating fingers 89 and 92 of a central group of four stop-operating levers 89, 90, 91, and 92 illustrated in connection with the central group of stops 33. (See Figs. 1, 6, and 7.)

The two intermediate stop-operating levers 90 and 91 of this central group of stop-operating

levers control stops which will be described hereinafter.

The four levers 89 to 92 of the central group of stop-operating levers are mounted side by side on a common pivot-pin 93 carried by an upwardly and rearwardly projecting frame-arm 94, and are provided with positioning springs 95 by which their forwardly projecting ends are normally held lifted. In addition to those forwardly projecting ends, the stop-operating levers have downwardly projecting ends 96, which extend downward from the pivot-pin 93 into co-operative relation with stop-operating cams 97, 98, 99, and 100 mounted on a cam shaft 101 which makes one rotation for each stocking-knitting cycle. The cams 97 and 100 for the two outer stop-operating levers 89 and 92 have two cam protuberances 103 and 104 each, to operate those stop-operating levers twice in each stocking-knitting cycle—one time by the protuberances 103 to lower the stops 71 and 72, and the other time by the protuberances 104 to raise those stops 71 and 72.

Each of the cams 98 and 99 for the two inner stop-operating levers 90 and 91 is circular for the greater part of its circumference, but is provided at one point with a depression 105; into which the inturned lower extremity of the downwardly projecting end 96 of the associated stop-operating lever 90 or 91 drops when such depression comes opposite that inturned end in the movement of the cam shaft 101. Thus the two inner stop-operating levers 90 and 91 are held depressed for the greater part of the cycle, and are allowed to rise only when the depressions 105 come into position to permit it.

These inner stop-operating levers 90 and 91 cooperate with pins 106 and 107 projecting upwardly from the higher ends of stop-levers 108 and 109 respectively, the lower ends of which stop-levers 108 and 109 are movable vertically downward and upward respectively into and out of the paths of the stops 25 on the #6 and #7 endless bands respectively. When the stop-operating levers 90 and 91 are down, as they are during most of the cycle, they hold the pins 106 and 107 depressed; and thus hold the lower ends of the stop-levers 108 and 109 raised, in non-stop position out of the paths of the dogs 25, so that the #6 and #7 endless bands and their associated yarn-carriers or thread-guides 20 may make full strokes as determined by the end stops 31 and 32. But when those stop-operating levers 90 and 91 are up, as they are when the depressions 105 come opposite the inturned extremities of the downwardly projecting ends of those stop-operating levers, they permit the pins 106 and 107 to rise; so that the lower ends of the stop-levers 108 and 109 will drop into their stop positions, in which they are in the path of and may engage the dogs 25 on the #6 and #7 endless bands respectively to limit the movements of those dogs toward the center of the machine, and thus to prevent those dogs and the associated #6 and #7 yarn-carriers or thread-guides from making full strokes and to limit each of them to short non-center-passing strokes at one end of the normal full stroke. It is during this latter condition, with the stop-levers 108 and 109 depressed, that the heel tabs 39 and 42 are knitted.

The stop-levers 108 and 109 may simply tend to drop to their stop positions by gravity; but desirably they are provided with springs 110, conveniently leaf springs, which tend to move them down to those stop positions.

The two stop-levers 108 and 109 are mounted by suitable pivot pins on opposite faces of a carrying bar 111, suitably mounted on and beneath the frame portion 50, as by being set in a transverse slot thereof and held in place by attaching screws 112.

The cam shaft 101 carries other cams, for operating the stop-releasing levers 36 of the end groups of stops at proper points in the cycle of operation; but the arrangement and operation of those cams and stop-releasing levers may be in accordance with the standard practice of the Wildman single-unit knitting machine and with what is shown in the aforesaid Howie and Krieble Patent No. 1,982,991.

The cam shaft 101 is operated by a pawl-and-ratchet mechanism 120—121, which conveniently has a suitable shield 122 for holding the pawl 120 disengaged from the ratchet 121 when that is desired. The pawl 120 is reciprocated vertically by a bell-crank 123, the lower end of which carries a roller 124 cooperating with a cam 125 on the continuously operating main shaft 126. That main shaft 126 also carries a cam 127 which actuates a roller 128 in the lower end of a bell-crank 129, the upper end of which carries a pawl 130 which cooperates with a ratchet 131 on the selector shaft 66; and the engagement between the pawl 130 and the ratchet 131 is controlled by a shield 132. The two shields 122 and 132 are suitably operated at proper times, as through Bowden wires 133 and 134 respectively, by pattern-controlled mechanism of the general types shown in the two patents referred to.

The operation is indicated generally in Figs. 14 and 15, and is as follows:

The stocking welt 37 (Fig. 14) is first knitted in the usual way, by the usual operation of the needles and sinkers on a single silk or cotton yarn supplied by the #1 yarn-carrier or thread-guide 20, that is reciprocated between the proper end or selavage stops 31 and 32; and when knitted is turned in the usual manner.

When the welt 37 has been knitted and turned, and usually when the flare 37a just below the welt 37 has been knitted, the pattern and selector mechanisms permit the #1 endless band 21 and thread-guide or yarn-carrier 20 to come to rest, with the associated stop 25 in home position; and puts into operation the endless bands and yarn-carriers #5, #6, and #7 to knit the leg of the stocking, with each of those three yarn-carriers supplying the yarn for every third course. This yarn may be silk. As the knitting of the stocking leg proceeds, there are narrowings 135 at the proper points, by the operation of the screw 34 to move the end groups of selavage stops 31 and 32 toward each other, and by the operation of the usual narrowing mechanism.

At some point during the knitting of the welt and the leg (Fig. 14), for no precise point is essential so long as the operation is completed before the knitting of the heel splices 40 and 43 is started, the shield 132 is moved to uncover the teeth of the ratchet 131. This permits the vertically reciprocating pawl 130 to operate that ratchet step by step, and through it the shaft 66 and cam 65, to raise the double-rack bar 63 and thus to move the slides 53 and 54 and the stops 71 and 72 outward from their innermost positions (Figs. 12 and 13), to positions that are as far outward (Fig. 11) as it is desired to have them for determining the initial inner boundaries of the reinforcements or splices 40 and 43 to be produced at the stocking heel. When those outer

positions are reached, the pattern mechanism moves the shield 132 to lift the pawl 130 from the ratchet 131, and thus to stop the outward movement of said slides and stops.

At one point in that outward movement of the slides 53 and 54 and stops 71 and 72, the pins 73 and 74 are carried beneath the depressing fingers 85 and 86, as is shown in Figs. 9 and 10. At that point in the operation, while the pins 75 and 76 lie below those depressing fingers 85 and 86, the pattern mechanism moves the shield 122 to uncover the teeth of the ratchet 121. This permits the vertically reciprocating pawl 120 to operate the cam shaft 101 step by step; to cause the cam protuberances 103 on the outer cams 97 and 100 to depress the stop-operating levers 89 and 92. (See Fig. 10.) This causes the depressing fingers 85 and 86, carried by those stop-operating levers, to engage the operating pins 75 and 76 and to push them and the stops 71 and 72 downward from the non-stop positions which they have been occupying (Figs. 13 and 9) into their lower or stop positions (Fig. 10).

Often it is desired that only one of the stops 71 and 72 be moved vertically to stop and non-stop positions. In that case only one of the outer cams 97 and 100 is provided with protuberances 103 and 104, say the cam 100 (the left-most one in Fig. 6) which controls the stop-operating lever 92 and the stop 72 for the #4 endless band 21. The stop-operating lever 91 is then idle; and the stop 71 is set in its down or stop position and remains there continuously, and may even be made immovable vertically as the stops are shown in the aforesaid Howie Patent No. 1,989,232. The operation contemplated in making the stocking blank of Figs. 14 and 15 contemplates that only the stop 72 be moved vertically in the operation, and that the stop 71 be continuously in its down or stop position; so that only the #4 splice-yarn-carrier and endless band will at times have a full-stroke movement, and the other or #3 splice-yarn-carrier and endless band will never move past the stop 71.

As the knitting of the stocking leg proceeds after the stops 71 and 72 are both in down or stop positions, with the #5, #6, and #7 carriers reciprocating and supplying yarn for the full stroke as determined by the end stops 31 and 32, the point is reached where the heel-reinforcements or splices 40 and 43 are to start. At that point, the pattern and selector mechanisms cause the #3 and #4 yarn-carriers, and their associated #3 and #4 endless bands, to come into operation. But although the #5, #6, and #7 yarn-carriers continue to operate for full strokes as controlled by the proper end stops 31 and 32, the #3 and #4 yarn-carriers both start with non-center-passing strokes; to which they are limited by the stops 31 and 71, and by the stops 32 and 72, respectively, with the stops 71 and 72 in or near their farthest-out positions, illustrated in Fig. 11 for the stop 72.

The knitting continues under these conditions for the courses that form the heel-reinforcements or splices 40 and 43. But during the knitting of these courses, the stops 71 and 72 may be and desirably are moved inward step by step for a desired distance from those farthest-out positions (Fig. 11), to produce a tapering splice that gradually widens toward the heel as is shown in Fig. 14. This is produced by the cam 65; which at this stage is operated, under the

control of the pattern mechanism, to lower the double-rack bar 63, and thus to move the stops 71 and 72 gradually some distance toward the center of the mechanism to lengthen the non-center-passing strokes of the #3 and #4 yarn-carriers.

When the knitting has reached the point where the heel-splices 40 and 43 are completed and the heel-tabs 39 and 42 are to be started, the cam 65 will have moved the stops 71 and 72 inward about far enough, or slightly farther (in the stocking shown), to align them with the stop-levers 109 and 108 respectively. (This is where Fig. 7 shows the parts.) At that point the pattern and selector mechanisms do several things, including the following:

- a. They cause the stop 25 for the #5 yarn-carrier and endless band to move to home position, and go out of action;
- b. They cause the pawl 120 to actuate its ratchet 121, and so the cam shaft 101, to bring the depressions 105 of the two middle cams 98 and 99 into action, to raise the middle stop-operating levers 90 and 91 and so to lower the central-group stop-levers 108 and 109 for the #6 and #7 yarn-carriers, and thus to limit those two yarn-carriers to non-center-passing strokes;
- c. They cause the pawl 130 to actuate its ratchet 131, and so the cam 65, to move the stops 72 and 71 as necessary to align them with the now-lowered stop-levers 108 and 109 respectively—which with the stocking shown involves moving the stops 72 and 71 slightly outward.

The central-group stop-levers 108 and 109 are at a fixed distance (fixed in any stocking-knitting cycle) from the center of the machine, and the stops 71 and 72 at this time are thus at that same distance from the center of the machine; so that together the stops 71 and 109 for the #3 and #7 yarns, and the stops 72 and 108 for the #4 and #6 yarns, determine the inner edges of the heel-tabs 39 and 42 respectively.

At this stage, and before starting the heel-tabs, the loops between those inner edges are taken from their needles, on a suitable comb, in the usual manner.

Then the heel-tabs are knitted; with yarn from both the #3 and #7 yarn-carriers forming every course of the heel-tab 39 at the right of the stocking blank (Fig. 14), and yarn from both the #4 and #6 yarn-carriers forming every course of the heel-tab 42 at the left of the stocking-blank. In the knitting of the heel-tabs, the stops 71 and 72 remain stationary, in line with the central-group-stops 109 and 108 for the #7 and #6 yarn-carriers, so that the inner edges of the heel-tabs will be straight. But during the latter part of the knitting of the heel-tabs the pattern mechanism desirably causes operation of the screw 34 to move its end stops 31 and 32 inward and of the transfer mechanism to produce the narrowings 136.

When the heel-tabs have been knitted, they are turned in the usual manner, to put the loops forming their inner edges on the proper outer group of needles; and the loops which during the knitting of the heel-tabs were held on the comb above referred to are returned to the central-group of needles from which they were taken. (See Fig. 15.) At this stage the screw 34 is operated to set the end stops 31 and 32 the proper distances from the center of the machine for starting the knitting of the stocking foot;

the cam 65 is operated to move the stops 71 and 72 as necessary (slightly inward in the stocking shown) to locate the beginnings of the inner edges of the cradle portions 41 and 44; and the pattern and selector mechanisms cause the #5 yarn-carrier to return into operation, and the middle cams 98 and 99 to operate the middle stop-releasing-levers 90 and 91 to raise the central-group stop-levers 108 and 109 for the #6 and #7 yarn-carriers so that those two yarn-carriers may resume making full strokes.

Then the stocking foot is knitted, as is indicated in Fig. 15. The procedure is desirably substantially like that of knitting the lower part of the stocking leg where the heel splices 40 and 43 are provided; desirably with all three of the #5, #6, and #7 yarn-carriers supplying silk yarn for the full stroke, each in every third course (although a smaller or larger number of yarn-carriers and yarns may be used), and with the #3 and #4 yarn-carriers supplying silk or cotton yarn for the reinforcing of the cradle portions 41 and 44 respectively.

In knitting the stocking foot there may be any desired narrowings 137; by pattern-controlled movements of the screw 34 to move the end stops 31 and 32 inward, and of the narrowing mechanism to produce the proper narrowing stitches. In addition, there is pattern controlled movement of the cam 65, and so movement of the stops 71 and 72, first outward and later inward as shown, to produce any desired shape of the cradle-portions 41 and 44, as is clear from Fig. 15. The early outward movement of the stops 71 and 72 in knitting the cradle-portions is wholly optional, and sometimes is omitted; but the inward movement of these stops 71 and 72, to provide cradle-portions which extend gradually closer toward the middle as the stocking toe is approached, is probably always or nearly always desirable.

Starting at any desired point before the stocking toe is reached, but usually about 15 to 50 courses before, my invention permits an entirely new operation to be obtained, in knitting the full-width-reinforced portion 41 just back of the toe portion 38. At this stage, the cam 65 has moved the stops 71 and 72 so close to the center of the machine that the operating pins 75 and 76 lie over the inwardly projecting ends of the lifting levers 77 and 78 respectively; as is shown in Fig. 12. The shield 122 is then moved, under pattern control, to uncover the ratchet 121, and the vertically reciprocating pawl 120 operates the cam-shaft 101 so that the cam protuberances 104 on the outer cams 97 and 100 depress the stop-operating levers 89 and 92 to tilt the lifting levers 77 and 78 to raise the stops 71 and 72 from their lower or stop positions (Fig. 12) to their upper or non-stop positions (Fig. 13).

If desired, this may be done with only one of these stops 71 and 72; and the operation indicated in Fig. 15 contemplates it only for the stop 72, and contemplates putting the #3 yarn-carrier out of action at this point.

When the stops 71 and 72 are thus raised, the associated #3 and #4 yarn-carriers can have full-stroke operation. If only the stop 72 is thus raised, as contemplated in Fig. 15, it is only the #4 yarn-carrier which is permitted full-stroke operation; and the #3 yarn-carrier is caused to move to its home position, and to become inactive, under control of the pattern and selector mechanisms; and it will be assumed that that is what happens.

The full-width reinforced portion 41 just back of the toe 38 is now knitted. In this knitting, silk yarn may be and preferably is supplied by the #5, #6, or #7 yarn-carrier, operating every course; and the reinforcing silk or cotton thread is supplied by the #4 yarn-carrier, operating every course. This is indicated in Fig. 15.

If desired—for instance if a heavier reinforcement with one silk thread and two cotton threads be desired per course—the full-width reinforcement 41 may have cotton threads supplied by both the #3 and #4 yarn-carriers, each operating every stroke.

When the full-width reinforcement 41 is completed, the pattern and selector mechanisms put out of operation the #3, #4, #5, #6, and #7 yarn-carriers, or as many of them as desired, and puts the #2 yarn-carrier into operation; and the toe portion 38 is knitted in any desired or usual manner.

Many variations in this general operation may be made. My invention makes it possible, for the first time in this type of knitting machine, for a yarn-carrier to have both a full-stroke operation and a non-center-passing operation and at the same time to have both ends of both types of operations variable in position.

I claim as my invention:

1. In a single-unit knitting machine having yarn-carriers mounted on endless bands provided with dogs by which they are operated and stopped, a central-group stop which is movable horizontally toward and away from the center of the knitting machine and which has vertically separated stop and non-stop positions respectively in and out of the path of a dog on one of said endless bands, and a stop-operating member that shifts said stop vertically in one direction if actuated while the stop is in one position in its horizontal movement and in the other direction if similarly actuated while the stop is in another position in its horizontal movement.
2. In a single-unit knitting machine having yarn-carriers mounted on endless bands provided with dogs by which they are operated and stopped, a central-group stop which is movable longitudinally of one of said endless bands toward and away from the center of the knitting machine and which has stop and non-stop positions separated from each other transversely of one of said endless bands and respectively in and out of the path of a dog on that endless band, and a stop-operating member that shifts said stop in one direction if actuated while the stop is in one position in its movement longitudinally of the endless band and in the other direction if similarly actuated while the stop is in another position in its movement longitudinally of said endless band.
3. In a single-unit knitting machine having yarn-carriers mounted on endless bands provided with dogs by which they are operated and stopped, a slide which is shiftable longitudinally of an endless band, a stop carried by said slide and shiftable transversely thereof into and out of the path of a dog on that endless band, and a stop-operating member which when actuated in one direction will shift said stop to stop position if the slide is in one longitudinal location but will shift the stop to non-stop position if the slide is in another longitudinal location.

ALBERT X. DESMONDS.
